UNITED STATES PATENT OFFICE.

AMOS S. BLAKE, OF WATERBURY, CONNECTICUT.

IMPROVEMENT IN METALLIC CARTRIDGES.

Specification forming part of Letters Patent No. 55,233, dated June 5, 1866.

To all whom it may concern:

Be it known that I, AMOS S. BLAKE, of Waterbury, New Haven county, State of Connecticut, have invented a new and useful Improvement in Cartridges; and I do hereby declare that the following is a full, clear, and exact description thereof, which will enable others skilled in the art to make and use the same, reference being had to the accompanying drawing, forming part of this specification, in which—

Figure 1 represents a cartridge made according to my invention. It is shown in this figure as it appears after firing. Fig. 2 is a peripheral view of the cartridge.

Similar letters of reference indicate like parts.

This invention consists in so making cartridges for breech-loading fire-arms as that the part which contains the powder and ball is separate and detached from that which contains the fulminate. This is accomplished by making the cartridge substantially in separate parts, which are only brought together in the act of loading. The part which contains the powder and ball is a hollow cylinder, closed at the end which receives the powder, but such end having a small perforation at its center, to enable fire from the explosion of the fulminate to reach the powder within. This end of the cylinder is inclosed, when the arm is loaded, within a cylindrical cap, one end of which is closed, said end having a recess that projects outward from its center, which recess contains the fulminate, and which, when the cap is placed over the other part of the cartridge, is opposite the perforation that reaches the powder. The fulminate may be held in place and protected by a water-proof preparation. The cap has a flanged head, by which it is withdrawn from the breech of a gun after firing, and on one side it has an oblong slot, which allows a portion of the side of the inner cylinder to be forced outward into the slot by the explosion of the powder, so as to connect the cap and inner cylinder together, for the purpose of drawing them both together from the breech when a retractor or other device operates against the flange of the cap.

The present mode of making cartridges in which the fulminate, powder, and ball are in-

closed in the same shell or cylinder-case is objectionable because of the danger attending them in the process of manufacture, and in handling and transporting them. I have endeavored to avoid this danger by making a cartridge whose shell is in two parts, detachable and separate. I also provide against the escape of gas from the rear of the cartridge when it is fired.

In the example of my invention here given, A is the cylindrical case which receives the powder and ball. It is plain, the rear end that receives the powder being closed, save by a small perforation to allow the explosion of the fulminate to reach through it to the powder. The place of the perforation is marked C, and it may be dented outward to bring the powder into close proximity with the fulminate. The letter B designates a cylindrical case of larger diameter than the other, so that it can be placed over its end, as seen in the description. The counter-bore of the gun may be enlarged to receive the case B, or that part of case A which is inclosed may be reduced in diameter if the bore is not enlarged. This case B forms a cap to the rest of the cartridge, and it has a flange at the edge of its closed end, to enable it to be thrown out of the breech of a gun by a retractor after firing. The center of the closed end of the cap or case B is projected, as seen at D, to form a recess within for a charge of fulminate, which may be covered and protected by a water-proof covering. An oblong slot, F, is cut on one side of the case or cap B, to enable the case A to be attached or made to adhere to the outer case by the effects of the explosion of the cartridge, which will force the adjacent part of case A into or against the edges of the slot, so as to enable both cases to be withdrawn from a gun or pistol by applying force to the flange E of the outer case.

This invention is applicable to all breech-loading fire-arms, large and small. By means thereof the danger of accidents from premature explosion is much lessened. The cases A, B can be carried in separate receptacles, and are only brought together in the act of loading.

It will be observed that the escape of gas toward the rear of the cartridge is effectually prevented by this construction.

I claim as new and desire to secure by Letters Patent—

As an improvement in cartridge-cases, the perforated cap B, with its oblong opening F, arranged to operate with the case A, so that by the expansion of the metal in explosion of the powder a portion of the case A will be

forced into the opening in the cap B, and the two parts be held together, substantially as described.

AMOS S. BLAKE.
